UNITED STATES PATENT OFFICE.

JOHN P. CLARY von CARLSBERG, OF WESTERLY, RHODE ISLAND, ASSIGNOR TO ATELIER
J. P. CLARY von CARLSBERG CO., OF WESTERLY, RHODE ISLAND, A FIRM.

DESIGN FOR A FINGER-RING.

49,630.

Specification for Design.

Patented Sept. 5, 1916.

Application filed June 26, 1916. Serial No. 106,068. Term of patent 7 years.

To all whom it may concern:

Be it known that I, JOHN P. CLARY von CARLSBERG, a citizen of the United States of America, residing at Westerly, in the county of Washington and State of Rhode Island, have invented a new, original, and ornamental Design for a Finger-Ring, of which the following is a specification, reference being had to the accompanying drawing, forming a part thereof, in which—

Figure 1 is a plan view of a finger ring

showing my new design. Fig. 2 is a view in elevation, and Figs. 3 and 4 are side views of the respective sides of the finger ring.

I claim:

The ornamental design for a finger ring as shown.

JOHN P. CLARY von CARLSBERG.

Witnesses:

JOSEPH T. MURPHY,
JOSEPH W. GAFFNEY.
